FOREIGN PATENT DOCUMENTS

EM 00771779-0001 * 3/2020

Primary Examiner — Paula Allen Greene*(74) Attorney, Agent, or Firm* — Birch, Stewart, Kolasch & Birch, LLP(57) **CLAIM**

The ornamental design for a bone conduction wireless headset, as shown and described.

DESCRIPTION

FIG. 1 is a front view of a bone conduction wireless headset showing my new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a perspective view thereof; and,

FIG. 8 is another perspective view thereof.
